UNITED STATES PATENT OFFICE.

JOSEPH J. PATCHETT, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,797, dated April 16, 1872.

Specification describing a new and original Design for a Carpet, invented by JOSEPH JAMES PATCHETT, of Halifax, in the county of York, England.

The accompanying photographic illustration fully represents my new design.

This invention relates to a new design for the main figure of a carpet, which has a square in the middle and semicircular projections on each side of the square, with lozenge-shaped ornaments in the projections and a star within the square, as shown. The invention also consists in the new design for the scroll ground-work of the carpet, as shown.

I claim as my invention—

1. The design for the main figure of the carpet, as shown.
2. The design for the groundwork of a carpet, as shown.

JOSEPH JAMES PATCHETT.
